UNITED STATES PATENT OFFICE.

GEORGE BICKELHAUPT, OF NEW YORK, N. Y.

SCUTTLE-LIFTER.

SPECIFICATION forming part of Letters Patent No. 668,435, dated February 19, 1901.

Application filed November 6, 1900. Serial No. 35,592. (No model.)

To all whom it may concern:

Be it known that I, GEORGE BICKELHAUPT, a citizen of the United States, and a resident of the city of New York, borough of Manhattan, in the county and State of New York, have invented a new and Improved Scuttle-Lifter, of which the following is a full, clear, and exact description.

The invention relates to operating mechanisms for sashes, scuttles, skylights, and like devices—for instance, such as shown and described in the Letters Patent of the United States No. 639,139, granted to me December 12, 1899.

15 The object of the present invention is to provide a new and improved scuttle-lifter arranged to permit the operator to easily open or close the scuttle and to automatically and securely lock the scuttle in a closed position.

20 The invention consists of novel features and parts and combinations of the same, as will be fully described hereinafter and then pointed out in the claims.

A practical embodiment of the invention 25 is represented in the accompanying drawings, forming a part of this specification, in which similar characters of reference indicate corresponding parts in all the views.

Figure 1 is a perspective view of the improvement as applied with the scuttle shown 30 in a partly-open position. Fig. 2 is an enlarged sectional plan view of the same with the scuttle closed and locked. Fig. 3 is a sectional side elevation of the same on the line 33 in Fig. 2. Fig. 4 is a sectional side elevation of the same on the line 44 in Fig. 2. Fig. 5 is a sectional side elevation of the same with parts in position for swinging the scuttle open, and Fig. 6 is a cross-section of the same on 40 the line 66 in Fig. 5.

The scuttle A is connected by the usual 45 hinges B to the upper end of the frame C, and on the under side of the scuttle A is secured a longitudinally-extending guideway D, preferably made of a square tube having a slot in the bottom and provided with transversely-extending teeth or notches D', as plainly indicated in the drawings. In the guideway D is mounted to travel a friction-roller E, journaled on the forward end of a lever F, fulcrumed at or near its middle at F' on one side of the frame C, so that when a swinging mo-

tion is given to the lever F in the direction of the arrow a' the friction-roller E causes an upward swinging of the scuttle A into an open 55 position, as shown in full lines in Fig. 1 and in dotted lines in Fig. 4. A catch G is fulcrumed at H on the forward end of the lever F, and said catch is adapted to engage the teeth D' of the guideway D, so as to hold the 60 lever F locked to the guideway D and support the scuttle A when in a raised position and at the time the lever F is released by the operator.

The catch G is provided with a downwardly-extending arm G', having an elongated slot 65 engaged by a pin I' on a spring-pressed bolt or latch I, mounted to slide in suitable bearings in a casing I², secured to or formed on the forward end thereof, so that when the 70 scuttle A is in a closed position, as shown in full lines in Fig. 4, the latch I engages the said keeper J at the time the catch G is out of engagement with the teeth D' of the guideway D. (See Fig. 4.) The catch G is also 75 provided with an upwardly-extending arm G², adapted to engage one end of a lever K, fulcrumed at or near its middle at K' to the under side of the scuttle A, the other end of said lever engaging a spring-pressed latch L, 80 mounted to slide in a casing L', attached to the under side of the scuttle A. The latch L is adapted to engage a keeper N, (see Figs. 2 and 3,) secured to the inside of the frame C at the forward end thereof, at the time the 85 scuttle A is closed, so that the two latches I and L securely hold the scuttle in a closed locked position, and thereby prevent persons from opening the scuttle from the outside of the building. The end of the lever K near 90 the arm G² engages a guideway K² to hold said lever in proper position.

On the latch I is secured one end of a rope O, extending along the under side of the lever F over the pulleys P P', secured to the 95 downwardly-curved end of the lever F. The rope extends from the pulley P' horizontally and forwardly and around a pulley P², journaled in the forked end of an arm attached to the lever F. The rope then extends upward 100 and passes over a pulley P³, secured to one side of the scuttle-frame C, the end of the rope hanging downward from the pulley P³ to be within convenient reach of the operator.

When the several parts are in the position shown in Fig. 4 and the scuttle A is securely locked to the scuttle-frame C by the latches I and L, as previously explained, and the operator desires to open the scuttle, it is necessary for the operator to pull on the rope O, so that the latter first imparts a sliding motion to the latch I and moves the same out of engagement with its keeper J, and as the said latch I is connected by the pin I' with the arm G' it is evident that a swinging motion is given to the catch G, causing the arm G' to impart a swinging motion to the lever K, so that the latch L is moved out of engagement with its keeper N, and consequently the scuttle A is unlocked. On a further pull on the rope O a swinging motion is given to the lever F in the direction of the arrow a', so that the scuttle A is swung into an open position, and as soon as the scuttle has reached the desired open position the operator releases the stress on the rope O, so that the spring of the latch I returns the latter to its outer position and in doing so imparts a swinging motion to the catch G to engage the catch with the corresponding teeth D' of the guideway D. When this takes place, the lever F is locked to the guideway D, and consequently the locked parts remain in position with the scuttle open, and the operator can now completely release the rope O.

When it is desired to close the scuttle A, the operator pulls on the rope O and imparts a sliding motion to the latch G, so that the latter is moved out of engagement with the teeth D', and upon the operator now gradually releasing the rope O the friction-roller E will travel in the guideway D and the scuttle A will close by its own weight, and when the scuttle moves into a final closed position on the scuttle-frame C and the operator releases the rope completely then the latch I engages its keeper J, owing to the pressure of the latch-spring, and in a similar manner the other latch L engages its keeper N by the action of the latch-spring. (See Fig. 3.)

By having the catch G pivoted on the lever F the pressure on the catch by the open scuttle is in the direction of the fulcrum H, so that the spring for the latch I is completely released at the time the scuttle A is completely relieved of all strain and the scuttle is open, and the spring is held under tension at the time the operator pulls the rope for opening or closing the scuttle, as above explained.

Having thus fully described my invention, I claim as new and desire to secure by Letters Patent—

60 1. An operating mechanism for scuttles, sashes, skylights and like devices, comprising a guideway on the device to be opened or closed, a lever having a sliding connection at one end with the guideway, so that when a swinging motion is given to the lever a corresponding movement is given to the device to be opened or closed, a catch carried by the

lever for engaging the guideway to hold the device in the position to which it has been raised, a latch for locking the closed device to its frame and with which the catch is operatively connected, and flexible means under the control of the operator, for operating said latches to unlock the device preparatory to opening it by the lever acting on the said guideway, as set forth.

2. An operating mechanism for scuttles, sashes, skylights and like devices, comprising a guideway on the device to be opened or closed, a lever having a sliding connection at one end with the guideway, so that when a swinging motion is given to the lever a corresponding movement is given to the device to be opened or closed, latches for locking the closed device to its frame, flexible means under the control of the operator, for operating said latches to unlock the device preparatory to opening it by the lever acting on the said guideway, and a catch on the lever and controlled by one of said latches, to throw the catch in or out of engagement with the said guideway, as set forth.

3. An operating mechanism for scuttles, sashes, skylights and like devices, comprising a guideway on the device to be opened or closed, a lever having a sliding connection at one end with the said guideway, a catch pivoted on the free end of said lever, and adapted to engage one end with a series of teeth on said guideway, so that when a swinging motion is given to the lever a corresponding movement is given to the device to be opened or closed, a spring-pressed latch mounted to slide on said lever and connected with said catch, and a flexible means under the control of the operator for operating said latch to unlock the device preparatory to opening it by the lever acting on the said guideway, said latch also controlling the movement of said catch, as set forth.

4. An operating mechanism for scuttles, sashes, skylights and like devices, comprising a guideway on the device to be opened or closed, a lever having a sliding connection at one end with the said guideway, a catch pivoted on the free end of said lever, and adapted to engage one end with a series of teeth on said guideway, so that when a swinging motion is given to the lever a corresponding movement is given to the device to be opened or closed, a spring-pressed latch mounted to slide on said lever and connected with said latch, a flexible means under the control of the operator, for operating said latch to unlock the device preparatory to opening it by the lever acting on the said guideway, said latch also controlling the movement of said catch, as set forth.

5. The combination with a guideway adapted to be secured to a scuttle or the like and provided with teeth, of a pivoted lever fitted to travel on the guideway, a pivoted catch

carried by the lever and adapted to engage the teeth of the guideway, said catch having a slotted member, a sliding latch for locking the scuttle closed, said latch being provided 5 with a pin engaging the slot of the member of the catch, and a rope secured to the latch, substantially as described.

6. The combination with a guideway adapted to be secured to a scuttle or the like and 10 provided with teeth, of a pivoted lever fitted to travel on the guideway, a three-armed catch pivoted to the lever, one member of the catch being provided with a slot, a sliding and spring-pressed latch provided with a pin

working in the slot of the member of the catch, 15 a rope for operating the lever and latch, a lever having one end extending into the path of one member of the catch, and a spring-pressed latch carried by the other end of said lever, substantially as described. 20

In testimony whereof I have signed my name to this specification in the presence of two subscribing witnesses.

GEORGE BICKELHAUPT.
